(57) **CLAIM**

The ornamental design for a swimming float, as shown and described.

DESCRIPTION

FIG. 1 is a top, front, right perspective view of a swimming float showing our new design;

FIG. 2 is a left side view thereof;

FIG. 3 is a rear view thereof;

FIG. 4 is a right side view thereof;

FIG. 5 is a front view thereof;

FIG. 6 is a bottom view thereof;

FIG. 7 is a top view thereof; and,

FIG. 8 is a view of FIG. 3 with the unclaimed portions removed for clarity.

The evenly broken lines represent portions of the article that form no part of the claimed design.
